ELECTROLUMINESCENT LAMP CONSTRUCTION

Elmer G. Fridrich, Cleveland, Ohio, assignor to General Electric Company, a corporation of New York

Application December 10, 1957, Serial No. 701,894

4 Claims. (Cl. 313—108)

This invention relates to electroluminescent lamps of the flexible laminated type and is more particularly concerned with the contacts or terminals of such lamps for the application of voltage thereto.

An electroluminescent lamp or cell comprises a layer of phosphor sandwiched between a pair of conducting plates or films at least one of which is transparent or light-transmitting. The electroluminescent cell of the present invention is of the type disclosed in Patent 2,774,004—Jaffe, assigned to the same assignee as the present invention, wherein the transparent conducting plate or layer is a flexible conductive sheet of compacted glass fibers. More specifically, the present invention is proposed as an improvement over the electroluminescent lamp construction described and claimed in copending application Serial No. 701,906 of Elmer G. Fridrich and Paul A. Dell, filed of even date herewith, and entitled "Electroluminescent Lamp and Manufacture Thereof," and assigned to the same assignee as the present invention. The electroluminescent lamp described therein comprises a flexible laminated assembly of electrically active layers encased in a thin envelope of thermoplastic material which is evacuated and completely heat-sealed all around its edges. The electrically active elements comprise an aluminum foil coated with a layer of high dielectric constant material which in turn is overcoated with a layer of electroluminescent phosphor. Overlying the phosphor layer is a sheet of conducting glass paper which extends less than all the way to the edges of the aluminum foil. The contacts or terminals of the lamp comprise flattened metal conductors or ribbons extending one in contact with the outer surface of the aluminum foil, and the other in contact with the outer surface of the conducting glass sheet, these metal ribbons being embedded one in each of the outer sheets of the thermoplastic envelope. The ends of the ribbons are connected to pieces of fine copper mesh whose inner ends are embedded in the thermoplastic envelope and whose outer ends project therefrom to provide the terminals of the electroluminescent lamp.

The object of the present invention is to provide a new and improved terminal construction for such an electroluminescent lamp.

A more specific object of the invention is to provide a terminal construction which is complementary to the thin flat nature of the flexible electroluminescent lamp and which will lend itself readily to engagement in a correspondingly flat socket into which the lamp may easily be inserted. Another object is to provide a terminal construction allowing an electroluminescent cell to be cut into sections with each section retaining suitable terminals.

Yet another object of the invention is to provide a terminal construction for such electroluminescent lamps which is adaptable to continuous strip production.

In accordance with the invention, a laminated flexible electroluminescent lamp or cell is provided with electrode

strips along at least one edge consisting of a pair of foils separated by an insulating sheet of plastic, one of the foil electrodes being in continuous contact with the aluminum foil of the cell and the other being in continuous contact with the conducting glass sheet.

In a preferred construction, the phosphor coated foil of the cell has a portion devoid of phosphor extending beyond the edge of the polyethylene envelope on one side and is folded thereover to lie flat against the underside 10 of the cell along one margin. A high-density polyethylene strip is inserted along the margin of the cell to cover the bare margin of the foil up to where it is bent around the polyethylene envelope. For the other electrode, a foil strip is placed to overlie the edge of the conducting 15 glass paper and is bent around to overlie the underside of the polyethylene envelope. The cell is thus provided with exposed continuous strip contacts on opposite sides of one margin of the envelope which may readily be engaged by a clamp type connector for energizing the cell.

For further objects and advantages and for a detailed description of preferred embodiments of the invention, attention is now directed to the following description and accompanying drawings. The features of the invention believed to be novel will be more particularly pointed 20 out in the appended claims.

In the drawings:

Fig. 1 is a pictorial view of a flexible laminated electroluminescent lamp embodying the invention, along with a suitable connector therefor.

Fig. 2 is a detailed exploded sectional view of the electrode terminal edge of the electroluminescent lamp of Fig. 1.

Fig. 3 is a view similar to that of Fig. 2 showing a variant of the invention.

Referring to Fig. 1, the illustrated electroluminescent lamp has one corner delaminated or peeled open to show the various constituent layers of the lamp. The cell 1 is a flat rectangular device made up entirely of flexible components laminated together and entirely sealed in plastic material. The lowermost film or sheet 2 and the uppermost sheet 3 which form respectively the underside and the topside of the envelope in the finished lamp consist of thermoplastic material which flows under heat and pressure and welds or fuses together along the margins. 40 The thermoplastic material selected, in addition to being light-transmitting and preferably fairly flexible, must be reasonably tough and stable and high-density polyethylene film of 0.003 inch thickness is preferred. A rectangular sheet of thin metal foil 4 coated with an insulating layer 5 of high dielectric constant material and a light producing layer 6 of electroluminescent phosphor is placed over the lowermost polyethylene sheet 2 leaving a clear margin all around. A sheet of conducting micro-fiber glass paper 7 is laid over the coated foil leaving a narrow margin of foil uncovered all around. Preferably a thinner sheet or film 8 of low-density polyethylene is placed over the conducting glass paper and conveniently is of the same size as the high-density polyethylene envelope sheets 2, 3 and extends to their margins.

The coated metal foil 4 may consist of dead-soft annealed aluminum of 0.0008" thickness coated with a thin insulating layer such as barium titanate dispersed in an organic polymeric matrix and over-coated with an electroluminescent phosphor such as zinc sulfide with a suitable activator and likewise dispersed in an organic polymeric matrix. A preferred organic polymeric matrix forming a dense tough film of high dielectric constant and good mechanical and thermal stability and consisting of cyanoethyl cellulose with a suitable plasticizer is described and claimed in copending application Serial No. 701,907 of Mary S. Jaffe, entitled "High Dielectric Constant Matrices for Electroluminescent Phosphors," filed

of even date herewith and assigned to the same assignee as the present invention. The barium titanate layer and also the phosphor layer, both dispersed in cyanoethyl cellulose, may be applied to the aluminum foil by spraying or preferably through the use of a doctor blade.

The conducting glass paper 6 consists of commercially available micro-fiber glass paper 0.001" thick which has been made conducting by dipping in a solution of a metal salt which upon drying and baking at an elevated temperature forms a conducting coating. A suitable solution consists of indium basic trifluoroacetate

with stannic chloride (SnCl_4) dissolved in an organic solvent such as ethylene glycol monoethyl ether acetate. Reference may be made to copending application Serial No. 347,617 filed April 8, 1953 of Mary S. Jaffe entitled "Conductive Coating on Glass," now U.S. Patent 2,849,339 for a more complete description of the materials and process used in making conducting glass paper.

In order to energize the electroluminescent lamp, it is necessary to apply an alternating potential across the conductive layers, that is to the aluminum foil 4 and to the conducting glass paper 7. Convenient electrodes or contacts for so doing are provided consisting of metal foil strips 10, 11 extending along one margin and overlying the plastic envelope, the strips being separated and insulated one from the other by means of a plastic insert strip 12 extending slightly beyond what would otherwise be the edge of the lamp along that margin.

The details of construction of the contact strips are best shown in Fig. 2 which is in the nature of an exploded sectional view. In the completed lamp, of course, the components shown in Fig. 2 are pressed and laminated together and appear as shown in Fig. 1. Referring to Fig. 2, aluminum foil 4, generally coated with a barium titanate layer 5 and overcoated with a phosphor layer 6, is provided with a margin 13 devoid of coating. This margin extends to and around the edge of the lower high-density polyethylene envelope sheet 2 and forms lower contact strip 10. Preferably, a heat-sensitive laminating adhesive is applied to the margin of the high-density polyethylene sheet 2 to assure better adhesion between the polyethylene and the aluminum foil where they join. The adhesive, for instance a silicone cement, may be applied by brushing on the edge of the high-density polyethylene sheet 2.

A narrow strip of high-density polyethylene is placed over the bare margin of foil 4 and forms the insulating polyethylene strip 12 previously mentioned with reference to Fig. 1. Strip 12 extends far enough inwardly into the cell lay-up to underlie the conducting glass paper 7 and extends far enough outwardly to provide protective insulation between lower contact 10 and upper contact 11. A thin strip 14 of soft low-density polyethylene (shown at an angle in Figs. 2 and 3 for illustrative purposes) is interposed between the edge of the insulating polyethylene strip 12 and the conducting glass paper 7. Strip 14 eases the abruptness of the step which the conducting glass paper must make in going over the edge of insulating strip 12 of high-density polyethylene when the lamp is laminated; the glass paper after it has been made conducting is quite fragile and rather brittle and might otherwise break at the step. Strip 14 also improves the adhesion of the cell components at the margin.

The upper contact consists of an aluminum foil strip 15 overreaching conducting glass paper 7 and extending out around the edges of low-density polyethylene film 8 and high-density polyethylene envelope sheet 3 and folded around the latter to form upper contact strip 11. The margin of high-density polyethylene upper envelope sheet 3 is likewise preferably coated with a heat-sensitive laminating adhesive to insure good bonding of contact strip 11 to the lamp envelope.

Connections to the contact surfaces may conveniently

be made by means of the flat connector shown at 16 in Fig. 1 and consisting of a molded piece of insulating plastic material 17, channel-shaped in cross section to provide a groove 18 which may be slipped over the edge 5 of the electroluminescent lamp to overlap the contacts. Within the groove 18 are positioned a pair of spaced connectors 19, 20 each provided with springy tongues 21, 22 forming two staggered series electrically insulated one from the other. The tongues of series 21 engage lower contact strip 10 and those of series 22 engage upper contact strip 11. The twisted wires 23, 24 are connected respectively to series 21, 22 and lead to a voltage source; the staggering of the tongues avoids short-circuiting the wires when the connector is disengaged 15 from the lamp.

Referring to Fig. 3, there is shown a variant of the invention wherein the contact strips, instead of being folded over the edge of the electroluminescent lamp envelope, are merely extended out flat to the side. This 20 makes for easier assembly on a continuous-strip production basis. As illustrated, coated aluminum foil 4 is extended beyond the edge of high-density polyethylene envelope sheet 2 as a non-coated strip 26. High-density polyethylene insulating strip 12 is made wider than in the embodiment of Fig. 1 in order to reach and project slightly beyond the outer edge of the laterally projecting contact strips. The upper contact strip 27 overreaches 25 the conducting glass paper 7 on one side and extends even with the edge of contact strip 26 on the other side. 30 The high-density polyethylene insulating strip 12 is preferably coated with a heat-sensitive laminating adhesive on both sides to insure good bonding of the aluminum foil contact strips.

In the embodiment of Fig. 3, it is not essential that 35 the margin of aluminum foil 4 be devoid of the barium titanate and phosphor layers inasmuch as it is the underside of the foil which is engaged by the connector. However it is preferable to have at least the outer edge devoid of phosphor in order to assure a good bond between aluminum foil 4 and high-density polyethylene insulating strip 12, and also to provide a more effective 40 hermetic seal with greater resistance to penetration of moisture.

It will be appreciated that instead of having both 45 contact strips on opposite sides of the same margin of the electroluminescent lamp, the strips may be provided on opposite margins or spaced longitudinal along the same margin in which case, of course, both contact strips may be placed on the same side of the electroluminescent lamp if desired, for instance on opposite edges of the 50 front face. Obviously, a number of variations of this kind are possible with the strip construction which has been described. The contact strip construction of the invention lends itself particularly well to continuous 55 band production techniques inasmuch as any particular length cut off from the band has a portion of the contact strip attached ready to serve as terminals.

While certain specific embodiments of the invention 60 have been described in detail, the same are intended as illustrative and not in order to limit the invention thereto. The scope of the invention is to be determined by the appended claims.

What I claim as new and desire to secure by Letters Patent of the United States is:

65 1. An electroluminescent cell comprising a laminated evacuated assembly including outer envelope sheets of thermoplastic material of which at least the front sheet has a light-transmitting portion and an electrically active assembly including a thin flexible metal foil having a coating of electroluminescent phosphor and a sheet of conducting glass fibers facing said coating, said outer envelope sheets being sealed together along their margins and overreaching the electrically active assembly, and a pair of contact foils extending out of said laminated assembly and separated by and laminated to an

intermediate thermoplastic strip serving as an insulator, one of said contact foils being a prolongation of the metal foil of the electrically active assembly and the other of said contact foils being a strip laid under the front thermoplastic envelope sheet and over-reaching the margin of the conducting glass sheet and in conductive engagement therewith.

2. An electroluminescent cell comprising a laminated evacuated assembly including an outer envelope of polyethylene sheets sealed together along their margins and an electrically active assembly including an aluminum foil having a coating of electroluminescent phosphor and a sheet of conducting glass fibers facing said coating, said outer envelope sheets overreaching the electrically active assembly, and a pair of contact foils extending out of said laminated assembly and separated and laminated to an intermediate polyethylene strip serving as an insulator, one of said contact foils being a prolongation of the aluminum foil of the electrically active assembly and the other of said contact foils being a strip laid under the overlying polyethylene envelope sheet and over-reaching the margin of the conducting glass sheet and in conductive engagement therewith.

3. An electroluminescent cell comprising a laminated evacuated assembly including outer envelope sheets of thermoplastic material and an electrically active assembly including a thin flexible metal foil having a coating of electroluminescent phosphor and a sheet of conducting glass fibers facing said coating, said outer envelope sheets being sealed together along their margins and overreaching the electrically active assembly, and a pair of contact foils extending out one edge of said outer envelope and folded back and laminated against opposite sides of said envelope along a margin thereof, one of said contact foils being a prolongation devoid of phosphor

25
30
35

of the metal foil of said electrically active assembly and the other of said contact foils being a strip laid under the front thermoplastic envelope sheet and overreaching the margin of said conducting glass paper, and an intermediate thermoplastic strip laminated between said contact strips.

4. An electroluminescent cell comprising a laminated evacuated assembly including outer envelope sheets of thermoplastic material and an electrically active assembly including a thin flexible metal foil having a coating of electroluminescent phosphor and a sheet of conducting glass fibers facing said coating, said outer envelope sheets being sealed together along their margins and overreaching the electrically active assembly, and a pair of contact foils having marginal portions extending out one edge of said outer envelope and laminated to opposite sides of an intermediate insulating thermoplastic strip projecting out said edge of said envelope, one of said contact foils being a prolongation of the metal foil of said electrically active assembly and the other of said contact foils being a strip laid under the front thermoplastic envelope sheet and overreaching the margin of said conducting glass sheet and in conductive engagement therewith.
